DESIGN FOR A FISH LURE

Walter J. Biernat, Detroit, Mich., assignor to Joseph L. Biernat, Edward M. Biernat, Thomas A. Biernat, and Walter J. Biernat, a partnership doing business under the firm name of Biernat Tackle Manufacturing Company, Detroit, Mich.

Application May 14, 1946, Serial No. 129,691

Term of patent 3½ years

(Cl. D31—4)

To all whom it may concern:

Be it known that I, Walter J. Biernat, a citizen of the United States of America, residing at Detroit, in the county of Wayne and State of Michigan, have invented a new, original, and ornamental Design for a Fish Lure, of which the following is a specification, reference being had therein to the accompanying drawing, forming a part thereof, wherein:

Figure 1 is a plan view of a fish lure embodying my new design;

Figure 2 is a side elevational view of the fish lure shown in Figure 1; and

Figure 3 is a front elevational view of the fish lure shown in Figure 1.

I claim:

The ornamental design for a fish lure, substantially as shown.

WALTER J. BIERNAT.
